[57] CLAIM

The ornamental design for a pair of automobile front quarter panel exterior surfaces, as shown and described.

DESCRIPTION

FIG. 1 is a top and side perspective view of the left front quarter panel exterior surface showing our new design;

FIG. 2 is a top and side perspective view of the right front quarter panel exterior surface;

FIG. 3 is a side elevational view of the left front quarter panel exterior surface;

FIG. 4 is a side elevational view of the right front quarter panel exterior surface;

FIG. 5 is a front elevational view of the left front quarter panel exterior surface; and,

FIG. 6 is a front elevational view of the right front quarter panel exterior surface.

The dash line showing of adjacent automobile parts is only for showing the surrounding environment and is not part of the claimed design.
